UNITED STATES PATENT OFFICE.

THOMAS J. MURPHY, OF ROCHESTER, NEW YORK, ASSIGNOR OF ONE-HALF TO JAMES P. B. DUFFY, OF ROCHESTER, NEW YORK.

ELECTRIC MOTOR.

1,401,548.

Specification of Letters Patent. Patented Dec. 27, 1921.

Application filed September 17, 1917. Serial No. 191,736.

To all whom it may concern:

Be it known that I, THOMAS J. MURPHY, of Rochester, in the county of Monroe and State of New York, have invented certain 5 new and useful Improvements in Electric Motors; and I do hereby declare the following to be a full, clear, and exact description of the same, reference being had to the accompanying drawings, forming a part of 10 this specification, and to the reference-numerals marked thereon.

My invention has to do with various improvements in electrical motor construction and is with a view to rendering more economical 15 the manufacture of small motors particularly, of either alternating, direct or universal type, such as are employed in the operation of fans, sewing machines, sound reproducing machines, and other apparatus 20 requiring only a comparatively small amount of power. More specifically, the invention is intended to eliminate the difficulty usually involved in obtaining proper alinement of the armature and field elements of a motor, 25 and in reducing the number of machine operations required in assembling the parts. A further object of the invention is to provide a simplified casting, constituting a support for both the armature and field and auxiliary 30 parts, and permitting of very readily assembling these parts in their correct operative relation. An additional purpose of the invention is to afford a simple and advantageous form of mounting for holding the 35 motor effectively in proper driving relation with the member to which power is transmitted. To these and other ends the invention consists in certain improvements and combinations of parts, all as will be herein- 40 after more fully described, the novel features being pointed out in the claims at the end of the specification.

In the drawings:

Figure 1 is a vertical sectional view with 45 parts in elevation showing the application of the motor to a turntable of a sound reproducing apparatus;

Fig. 2 is a sectional view of the motor;

Fig. 3 is a similar sectional view illustrating a modified arrangement;

Fig. 4 is a side elevation;

Fig. 5 is a side elevation looking at one side of Fig. 4;

Fig. 6 is a plan view of the upper side of 55 the motor;

Fig. 7 is a sectional view on the line 7^a—7^a of Fig. 5, and Fig. 8 is a sectional view taken on line 8^a—8^a of Fig. 1.

Similar reference numerals in the several figures indicate the same parts.

The invention is susceptible of various applications in electric motor apparatus, and while peculiarly fitted for small work, it may likewise be adapted with advantage to other and larger electric machines and the 60 particular arrangement which I am disclosing here is intended by way of example of a practicable manner of carrying out the improvements.

Referring to Figs. 2, and 4 to 7, the structure comprises a supporting frame having oppositely disposed bearings 1 and 2 which receive the ends of an armature shaft 3. The supporting frame or loop member also embodies arms 4 at each end and longitudinal portions 5 connecting the bearings 1 and 2 before mentioned. 6 designates the armature mounted upon the armature shaft 3, preferably through an intermediate sleeve 7. 6^a indicates the commutator carried on 70 sleeve 7 and 7^a the brushes received and supported in suitable openings in the longitudinally extending members 5 carrying the bearings. In the assemblage of the parts, the armature containing the sleeve 7 can be 75 positioned within the frame, after which the shaft is inserted from one end of the frame and forced through the sleeve 7 until it is engaged properly in the bearings 1 and 2. In Fig. 3 I have shown a slightly modified 80 form that permits inserting the armature and shaft already assembled through one end of the frame. To this end, the frame may be provided with a removable end plate 8 which carries a bearing 9 for the armature 85 shaft and is secured within an opening in the end of the frame. The opening referred to will be of sufficient size to admit the armature.

10 designates the field element, which may 100 be of laminated formation and is arranged outside the frame, surrounding and in contact with the longitudinal portions 5. The field, when laminated, comprises a multiplicity of plates which are slipped on over the 105 frame; the lowermost one resting upon an annular shoulder 11 which is formed integral with the frame, and carried by the longitudinal portions 5. The shoulder 11 constitutes a stop for one end of the field 110

element, while the opposite end is engaged by a removable retaining device, preferably in the form of a ring 12. The ring 12 fits over the frame against the uppermost lamination of the field element and is held in place by the suitable securing means. To this end, the ring 12 has formed thereon extensions 13 which project toward the annular shoulder 11 and receive attaching screws or other similar devices 14 which co-operate with the annular shoulder of the frame and engage the extensions on the removable ring, serving to hold the latter in fixed and rigid relation, and thus retaining the field element in place. This arrangement is of marked advantage in that it permits the supporting frame to be cast as a single unit, with the bearings of the armature shaft and the position of the field element predetermined. These parts can be readily brought into their operative relations upon the supporting frame, which insures accuracy of position and eliminates the difficulty and time required ordinarily in machining various parts to obtain a correct relative position between the armature and the field.

The armature shaft 3 is provided with a driving member in the form of a pulley 15, which in the present instance engages the edge of a turntable 16 and drives the latter frictionally. It is desirable that the pulley 15 be held yieldably against the driven member or turntable 16, but with sufficient pressure to obtain the desired friction between the parts. This I accomplish by pivotally mounting the motor between the stationary arms 17, which are provided with trunnions 18 that engage openings in the aforesaid extensions 13. Positioned between the arms 17 is a stationary abutment 19, while 20 is a rod extending through the abutment 19 and provided with a yoke 21 pivoted to the end 22 of the motor frame. The rod 20 is slideable in the abutment 19, and on opposite sides thereof are springs 23 and 24, the latter being held in place by a nut 25, which is adjustable to vary the tension under which the motor is held in driving contact with the driven member. This arrangement holds the motor firmly, yet yieldably, and effectively prevents undue vibration or chatter. 26 are felt washers located against the abutment 19, and 27 are metal washers which engage the springs, the felt washers serving to deaden the sound caused by relative movement of the parts.

The motor trunnions are also preferably mounted on felt bushings 28, the latter being held in place against the shoulders 21, by means of fiber washers 29. The washers 29 are retained by heads 30 on the trunnions. There is a slight clearance between the trunnions 18 and the shoulders 31, sufficient to prevent their coming into engagement, so

that the motor rests entirely on the felt supports 28, and is yieldable thereon.

Among the advantages of my construction may be mentioned the fact that when my machine is used as an alternating current motor, the longitudinal portions 5 together with the arms 4 act as a short circuited winding inductively co-operating with the field and armature to reduce the self induction of the field while at the same time acting as a combined support and clamping means for the stator laminations. By making the longitudinal portions perform these two functions, it will be seen that a beneficial saving in weight and external dimensions of the machine is possible.

I claim as my invention:

1. In a dynamo electric machine, the combination with a rotor of a stator comprising bearings therein for the rotor, longitudinal portions connecting said bearings and in inductive relation to the field, external shoulders on said longitudinal portions, stator laminations supported externally on said longitudinal portions and a clamping member on said longitudinal portions co-operating with said shoulders to secure the laminations in place, the stator laminations being provided with pole pieces between and spaced from said longitudinal portions. 95

2. In a dynamo electric machine, the combination with a rotor, of a stator comprising oppositely disposed bearings therein for the rotor, longitudinal portions connecting said bearings, laminations supported by said longitudinal portions and surrounding the same, windings on said laminations arranged to have said longitudinal portions in inductive relation to the stator field. 100

3. In a dynamo electric machine, the combination with an armature, of a field frame comprising oppositely disposed integral bearing housings therein for the armature, longitudinally extending portions integral with and connecting said bearings, laminations supported by said longitudinal portions and surrounding the same, windings on said field frame and armature to produce co-operating magnetic fluxes, said longitudinally extending portions being in inductive relation with one of said fluxes. 110

4. In an alternating current motor the combination with a rotor, of a stator comprising oppositely disposed bearings therein for the rotor, longitudinal portions integral with and connecting said bearings, laminations supported by said longitudinal portions and surrounding the same, windings on said laminations arranged to have said longitudinal portions in inductive relation to the stator field. 120

5. An electric apparatus comprising a frame having oppositely arranged bearings and longitudinal portions connecting the same, an annular member upon said longi- 130

tudinal frame portions, a field element supported by said annular member, a retaining member for said field element having extensions projecting in the direction of said annular member, and means connecting said extensions with said annular member to hold the field element in contact therewith.

5. In an electric motor, the combination with stator laminations and a rotor, of a

molecularly integral loop member having integral therewith bearing housings for said rotor and supporting said stator laminations, and windings on said stator and rotor to produce field and armature fluxes, said loop member being inductively related to one of 15 said fluxes as a short circuited winding.

THOMAS J. MURPHY.
